CLAIM

The ornamental design for a candle sconce, as shown and described.

DESCRIPTION

FIG. 1 is a front perspective view of a candle sconce showing my new design;

FIG. 2 is a front elevational thereof;

FIG. 3 is a right side elevational view thereof;

FIG. 4 is a left side elevational view thereof;

FIG. 5 is a bottom plan view thereof; and,

FIG. 6 is a top plan view thereof.

The broken lines shown on the drawings are for illustrative purposes only and form no part of the claimed design.
